DISPENSING DEVICE FOR CARTRIDGES OF
CALKING MATERIAL AND THE LIKE

William A. Sherbondy, Shaker Heights, Ohio

Application October 6, 1947, Serial No. 778,119

6 Claims. (Cl. 222—326)

1

This invention relates to a dispensing device for calking material and the like, comprising a handle in which one end of a cartridge adapted to contain such material may be mounted, the handle carrying means to engage the far end of the cartridge and hold it in place and being equipped with manually operable feeding mechanism to expel the contents from the cartridge. The object of the invention is to provide an extremely simple device for securing the cartridge in place, enabling the expulsion of the contents as desired by manipulation of a suitable hand lever on the handle.

In its preferred form my invention employs a cartridge in the form of a paper tube having at one end an internal cap which may act as a plunger in extruding material, and at the other end a cap having a central opening through which the extrusion takes place. A spout, which may be carried either by the cartridge itself or by the dispensing apparatus, registers in use with the discharge opening. When the discharge opening, or spout if one is mounted on the cartridge, is closed by a suitable frangible strip or removable plug, the cartridge with its two caps forms a ready shipping container for the calking material.

When it is desired to use the cartridge, it is only necessary to mount it in the apparatus, which is equipped with a spring loop or bail carried by the handle and adapted to overhang the front end of the cartridge to hold it in place.

The discharge apparatus may comprise a pusher rod, hand lever and suitable mechanism operated thereby to advance the rod and means to retain the gain made. Such pusher acts to advance the internal cap as a plunger to force out the seal and then discharge the contents through the spout. When the cartridge has been emptied, the release of the retaining device allows the pusher rod to be withdrawn, whereupon the used cartridge may be discarded and a fresh one installed.

A preferred form of the invention is illustrated in the drawings hereof and is hereinafter more fully described and the essential novel features are set out in the claims.

In the drawings, Fig. 1 is a side elevation of my dispensing device with the cartridge mounted therein, the view being partially broken out and in section adjacent the discharge end of the cartridge; Fig. 2 is a fragmentary vertical section through the handle and the rear portion of the mounted cartridge; Fig. 3 is a fragmentary plan of the same parts; Fig. 4 is a front section taken on the line 4—4 on Fig. 1 looking rearwardly;

and Fig. 5 is a rear section taken on the line 5—5 on Fig. 1 looking forwardly.

As shown in Figs. 1 and 2, 10 indicates the body of the cartridge, which is a paper tube similar to a mailing tube preferably spirally wound. 20 indicates an internal cap at the head end of the cartridge, which is preferably a sheet metal member having an internal flange leading toward the end of the tube and snugly engaging the wall thereof. 30 indicates the external cap at the discharge end having a central discharge opening. The discharge spout 36 is shown in Fig. 1 as mounted in this opening though it may be carried by the dispensing apparatus. In either case it registers with the opening in use.

The cartridge with its two caps and with the discharge opening closed (either by a suitable frangible strip across the opening or a removable plug in the spout, if the spout is mounted on the cartridge) constitutes the shipping container for the calking compound or other material.

I have shown the closure 30 as comprising a disc-like member having an external flange 31 to engage the exterior of the tube and then an internal annular portion 32 to engage the interior. From the inner edge of the annular portion 32 there is a transverse disc-like part 34 having the round central opening 35. The two walls 31 and 32 flare from each other slightly so that the cap may be readily placed over the end of the paper tube and being forced lengthwise of the tube will pinch the material of the tube between the external flange 31 and the internal wall 32.

The spout 36 may consist simply of a sheet metal member bent onto itself to produce a nearly complete tube having a flange 38 at the inner end. This tube may be shoved from the inner face of the cap outwardly until the flange 38 abuts the disc-like portion 34 of the cap and the resilience of the split tube tending to open it will hold it in place. When in place the longitudinal slot between the meeting edges of the sheet making the spout is substantially closed.

In shipping the container carrying the spout, I provide a plug of rubber or other suitable material 39 in the spout adjacent its discharge end. If the container is shipped without the spout the discharge opening is closed by a thin readily frangible strip of material secured to the inner face of the cap and extending across the opening.

When the cartridge is to be used it is placed in the manual apparatus about to be described, which may operate a pushing rod to push the internal cap 20 into the tube, and thus extrude the material through the opening at the discharge

end. The force of the advancing material forces out the plug in the spout or breaks the frangible seal on the cap, as the case may be.

The handle referred to comprises a member 40 preferably made of sheet metal doubled forwardly on itself to provide a body portion 41 and a hand grip 42, each having two spaced walls. The body portion is flanged outwardly to each side to 43 at its forward end. These flanges are riveted to a cup 45 in which the rear end of the cartridge seats.

The pushing mechanism comprises a rod 50 extending through the body 41 of the handle and through the cup 45 and carrying at its forward end a disc 52 adapted to engage and advance the internal cap 20 as a piston. To advance the rod and retain the gain made, I provide in the space within the body of the handle one or more normally vertical plates 60 loosely embracing the rod and pressed rearwardly in a vertical position by a compression spring 62. A handle 63 pivoted in the hand grip has a lug 64 at its upper end adapted to engage the lower portion of the rearmost plate 60 and cant the plates to bite into the rod and thereby shove it forward, against the action of the spring, to advance the piston. This same spring acts to maintain the lever normally projecting forward from the hand grip, as shown in Fig. 2, and the rearward movement of the lever by the fingers of the operator's hand embracing the hand grip thus advances the rod.

The gain made by each advancement of the rod is retained by a detent pawl 70 at the rear of the handle body, this pawl having an opening embracing the rod. A spring 72 is provided to maintain the pawl 60 normally in an inclined position to bind against the rod. The pawl is pivoted to the hand grip by means of having its lower end 74 extending through an opening in the grip.

As the operation of the handle advances the rod, such movement swings forward slightly the detent pawl so that the rod may pass freely through it. At the end of the advancing movement however the spring 72 acting on the pawl canters it toward the rear to bind the rod and thus retain the gain made. At the end of the discharge movement the rod may be released by merely pushing forward the upper end of the detent pawl and then the rod with its pusher plate may be readily withdrawn by the projecting end 51 of the rod, which forms a handle therefor.

To hold the cartridge in place when the rear end thereof is seated in the handle sleeve or cup 45, I provide a bail 80 which is pivoted at 81 to the handle body and is adapted to extend at its farthest portion across the discharging end of the cartridge and thus hold the cartridge in place with the other end in the handle sleeve. This bail is of wire formation, its free ends are pivoted to the handle by means of turned portions 83 which lie between the rear wall of the cup 45 and the adjacent flange 43 of the hand grip, this flange being bowed rearwardly at 47 to receive such inward portion of the bail pivotally. The extreme ends of the bail are bent longitudinally rearwardly to form stops holding the bail in place and to limit the swing thereof, as such end portions come against the flanges of the handle.

At the forward end or intermediate portion of the bail the two legs thereof are first bent inwardly as at 85, Fig. 4, and downwardly at 86 and then upwardly in arcuate formation 87 to define substantially a circle and then are con-

tinued to form the connecting U-shaped loop 88. The arcuate portion is adapted to embrace snugly the spout on the cartridge and thus position the cartridge at that end, or if desired to carry a spout for a non-spouted cartridge. The U-shaped portion extends upwardly above the cartridge as shown in Fig. 1 and forms a convenient handle for positioning or disengaging the bail loop from the spout. Such upper portion is preferably inclined forwardly from the cartridge, as shown at 89, for convenient handling.

In mounting the cartridge the bail is swung to idle position and the head end of the cartridge is shoved into the handle sleeve and then the bail is sprung over the far end. The straight legs of the bail are of such length with reference to the cartridge that the looped transverse portion of the bail engages snugly against the outer face of the end cap 30 of the cartridge and thus holds it effectively seated against the transverse end of the handle sleeve 45.

If the spout is carried by the cartridge the intermediate portion 87 of the bail which has a restricted entrance is simply sprung across the spout in positioning the bail in working position. If desired, however, the spout may be carried by the bail itself being mounted in this portion 87. When so mounted the dispensing apparatus is well adapted for operation with a cartridge having at the discharge end a central opening but no spout. Therefore in either case the bail in active position snugly embraces the spout and the spout registers with the discharge opening.

It will be seen that the resilience of the bail then holds the cartridge effectively in this position so that as the hand lever is operated the disc on the push rod 50 engaging the plunger cap 20 within the cartridge forces the body of material lengthwise of the cartridge and extrudes the end-most portion through the discharge opening. At the beginning of the operation such extrusion will break the seal or push out the rubber plug in the spout and thereafter feed the plastic material as desired.

It will be seen that my manually operated apparatus is an extremely simple and relatively inexpensive construction; that the cartridge whether equipped with a spout or otherwise may be readily mounted therein and when so mounted a complete calking gun is provided. Such gun has readily operable manual mechanism for extruding the material through the discharge spout, enabling use of the apparatus in the usual manner of a calking gun. The cartridge may remain in the apparatus as part of the complete gun until the material has been entirely used. Thereafter a mere manual pressure on the transverse looped portion at the far end of the wire bail will free the used cartridge and enable the installation of a fresh one.

I claim:

1. In a dispensing apparatus for viscous material, the combination of a handle, a pusher carried thereby, and a wire bail attached to the handle and having its intermediate portion adapted to extend across the outer end of a cartridge seated against the handle, said intermediate portion providing two spaced inwardly-concave regions to engage opposite sides of a spout associated with the outer end of the cartridge and a U-shaped spring loop connecting said concave portion beyond the region of the spout and projecting free of the outer end of the cartridge to form a finger grip.
2. In a dispensing apparatus for viscous ma-

terial, the combination of a handle provided with a seat for the rear end of a cartridge, a pusher carried by the handle, and a wire bail pivotally mounted on the handle and having an intermediate portion adapted to engage the front end of a cartridge whose rear end engages said seat, said intermediate portion being in the form of a loop having two inwardly facing concave portions adapted to engage a spout by spring action, said concave portions being connected by a U-shaped portion projecting beyond the periphery of the front end of the cartridge to form a finger grip.

3. In a dispensing apparatus for viscous material, the combination of a handle provided with a seat for the rear end of a cartridge, a pusher carried by the handle and having an intermediate portion adapted to engage the front end of a cartridge whose rear end engages said seat, said intermediate portion being in the form of a loop having inwardly facing concave sections to engage opposite sides of a spout associated with the front end of the cartridge and U-shaped portion interconnecting the concave sections, said U-shaped portion being bent forwardly relative to the plane of the front end of the cartridge to form a finger grip.

4. In a dispensing apparatus for viscous material, the combination of a hollow handle having outwardly extending flanges at its forward end, a forwardly facing cup having a disc-like portion to which the flanges are secured, each of said flanges having two rearwardly offset channel formations extending in a diametric plane of the cup, a bail having inturned end portions at the ends thereof extending between the disk-like portion of the cup and said channel formations of said flanges, said bail having an intermediate portion adapted to overhang the front of the cartridge.

5. In a dispensing device for viscous material, the combination of a sheet metal handle comprising two spaced side walls interconnected by a rear wall, means for holding a cartridge to the handle, a plunger rod slidably supported by said handle and adapted to move axially into the cartridge, an operating lever pivoted to said

5 handle, means operated by said lever to feed said rod into the cartridge step-by-step, and a detent for said rod comprising a strip having one end extending in an opening through said rear wall of said handle to form a pivot for said strip and extending along the outside of said wall and transversely of said rod, said strip having an opening therein through which said rod extends, said opening having a diameter greater than the rod diameter whereby the edges of said opening in said strip bind said rod when said strip is moved about its pivot from said handle and release said rod when moved toward said handle, and a spring interposed between said wall and said strip to urge said strip into binding relation with said rod.
